UNITED STATES PATENT OFFICE

HAROLD E. ADAMS, OF SOUTH NORWALK, CONNECTICUT, ASSIGNOR TO NASH ENGINEERING COMPANY, OF SOUTH NORWALK, CONNECTICUT, A CORPORATION OF CONNECTICUT

CONTROL MECHANISM FOR SEWAGE EJECTORS

Application filed October 22, 1933. Serial No. 314,081.

This invention relates to a mechanism for controlling the operations of a plurality of sewage ejectors of the general type shown in the prior patent to Jennings No. 1,492,171, issued April 29, 1924.

A battery of several such ejectors is frequently required in large sewage stations and it is one important object of my invention to provide mechanism for causing automatic operation of such ejectors in a predetermined order.

Further features of my invention relate to the provision of means for varying such predetermined order, to the provision of means for permitting automatic operation in the order of filling, and to the provision of means permitting manually controlled operation of any ejector at any time.

A further object of my invention is to provide interlocking devices preventing concurrent automatic operation of more than a single ejector. I have also provided means to indicate whether or not a particular ejector is full and to indicate when a particular ejector is being emptied or "blown".

My invention further relates to arrangements and combinations of parts which will be hereinafter described and more particularly pointed out in the appended claims.

A preferred form of the invention is shown in the drawings in which

Fig. 1 is a diagrammatic view of the control panel;

Fig. 2 is a diagrammatic view of the control circuits;

Fig. 3 is a front elevation of the pneumatic mechanism for controlling the blowing of a sewage ejector;

Fig. 4 is a sectional side elevation of the selector device;

Fig. 5 is a side view thereof, looking in the direction of the arrow 5 in Fig. 4; and

Fig. 6 is a detail sectional view, taken along the line 6-6 in Fig. 5.

Blowing apparatus and pneumatic control thereof

Referring to Fig. 3, I have indicated a type of sewage ejector such as is shown in the Jennings Patent No. 1,492,171, and comprising

ing a sewage ejector which operates by allowing the sewage to flow by gravity into a vented closed tank 10. When the tank is full, a float valve 12 causes the closing of the vent through the operation of a suitable pilot switch (not shown) and causes air to be forced into the tank, from which the sewage is thereby ejected. Check valves 13 and 14 prevent the flow of sewage in the reverse direction. Briefly stated, this is the operation of the sewage ejectors which my apparatus is designed to control. For a more complete description of this type of ejector, reference is made to the prior Jennings patent.

The tank 10 is commonly referred to in the trade as a sewage "pot" and the operation of forcing the sewage therefrom is known as "blowing the pot".

I have provided pneumatic control of the air supply for blowing the pot 10. A combination valve 15 is connected by a pipe 16 to the pot 10 and this valve has an air supply connection 17 and a vent connection 18. Two valves 19 and 20 are mounted on a plunger 21 and control the connection of the pipe 16 to the air supply pipe 17 or to the vent pipe 18. The plunger 21 rests upon a diaphragm 22 in a casing 23 connected by a pipe 24 to a casing 25 positioned between a pair of control valves 26 and 27.

The valve 26 is adapted to connect the casing 25 to a source of air pressure, and the valve 27 is adapted to connect the casing 25 to the atmosphere. The valve 26 is normally closed, the valve 27 is normally open, and the diaphragm 22 is normally in its lower position. The valve 19 is thus normally closed, and the valve 20 normally open, and the ejector pot 20 is thus normally connected to the atmosphere, permitting flow of sewage by gravity into the ejector pot.

The valves 26 and 27 are controlled by magnets 28 simultaneously operated. When both valves are raised, the air connections are reversed throughout, air pressure is admitted through the pipe 24 to the diaphragm casing 23, the valve plunger 21 is raised, the valve 20 is closed and the valve 19 is opened to admit air under pressure through the pipe 16 to cause emptying or blowing of the pot.

10. When the magnet circuit is broken, the valves resume their normal position as first described.

5   *General system of air control*

In my improved controlling apparatus, I have provided very flexible means for controlling the blowing of a battery of ejector pots in a variety of combinations.

10   In the first place, I have provided means for blowing the pots successively in predetermined order, and I have also provided means for varying the order at the will of the operator.

15   I have also provided means available when desired for causing the pots to blow in hit-or-miss order or in the random order of filling.

With either method of operation, I have provided interlocking devices for preventing 20 the blowing of more than a single pot at any one time.

In addition to these control devices, I have provided test switches by which any pot may be blown at any time under manual control, 25 and I have provided red and green lights, or other signal devices, for indicating when each separate pot is full, and also when each pot is in the operation of being blown.

I also provide means for cutting out any 30 separate pot from the electrical control for purposes of repair or otherwise, without interfering with the selective or automatic operation of the remaining pots.

35   *Control apparatus*

I will now separately describe the different parts of my control apparatus and the method of operation thereof.

Referring to Fig. 1, I have shown a typical 40 control panel illustrating diagrammatically the different elements of my control apparatus, as applied to a battery of three ejectors.

At A, I have shown the red and green signal lights indicating which pots are full 45 and which pots are blowing.

At B, I have indicated the manually controlled selector switch by which five different sequences of operation may be secured. Assuming that the pots are numbered 1, 2 and 50 3, the selector gives the orders 1-2-3 or 1-3-2 and also, in case any single pot is disabled, it gives the orders 1-2, 1-3, or 2-3.

At C I have indicated a six pole, double-acting switch by which the apparatus may be placed under the control of the selector device or may be set to operate hit-or-miss, in the order of filling.

At D I have indicated the main power lines 60 and the main control switch and fuses therefor.

At E, I have indicated test switches for the three ejector pots, the operation of which will be hereinafter described.

65   At F, I have indicated magnetic switches

for controlling the operation of the several pots, and at G I have shown six pole, single-acting safety switches by which any one of the pots may be cut out of operation for repairs or for other purposes.

70   *Selector device*

Referring particularly to Figs. 4 to 6, my improved selector device comprises a panel 30 and a sub-panel 31, formed of suitable non-conducting material and secured in spaced relation by bolts 32 and bushings 33.

A main shaft or stud 34 is secured in fixed position in the center of the sub-panel 31 and provides a journal for a sleeve 35, on which a selector hand wheel 36 and a selector disc or spider 37 are secured.

The spider 37 has six arms 38 extending radially therefrom and indicated in Fig. 2 as 38A, 38B, etc., each of said arms having a contact point 40 connected by a loosely coiled wire 41 to a terminal 42 fixed in the sub-panel 31. The contact spider 37 has a movement of less than sixty degrees, so that the wires 41 maintain their connection between the contacts 40 and the terminals 42 in all positions of the spider.

The contacts 40 engage terminals 44, also fixed in the sub-panel 31 and connected by wires 45 to terminals 46, 47 or 48 in the double control switch C by which the system of operation is determined.

There are thirty of the terminals 44, mounted in the sub-panel 31, and the wires 45 from these thirty terminals are assembled in three groups or cables, as indicated in Fig. 2. The numerals 1, 2 and 3 on the contacts 44 indicate that these numbered contacts control sewage ejectors having corresponding numbers.

The details of operation, as controlled by the selector, will be hereinafter described.

There are six terminals 42 in the sub-panel 31, indicated in Fig. 2 as 42A, 42B, etc., which terminals are engaged successively by a contact member 50 mounted in a supporting disc 51 and yieldingly pressed outward by a coil spring 52.

A six tooth ratchet 53 (Fig. 5) is secured to the disc 51, the disc and ratchet being freely rotatable on the fixed main shaft or stud 34. A hook pawl 54 is mounted on an arm 55, rotatable on a bushing 56 (Fig. 4) fixed to the end of the main shaft 34. A stud 57 is fixed in the arm 55 and extends through a transverse slot 58 in an actuating rod 59.

The rod 59 is slidable in a bearing 60 and is yieldingly drawn to the right, as viewed in Fig. 5, by a coil spring 61, to retract the pawl 54. The opposite end of the rod 59 is pivoted at 62 to the head 63 of the plunger 64, extending within a solenoid coil 65 (Fig. 5).

When current passes through the solenoid, the rod 59 is drawn to the left, as viewed in Fig. 5, turning the ratchet 53 and plate 15

51 through an angle of sixty degrees, thus advancing the contact 50 from one terminal 42 to the next terminal in order.

The contact 50 is electrically connected by 5 the spring 52 to a collector ring 67 engaged by a spring contact 68 (Fig. 6), mounted on a stud 69 fixed in the sub-panel 31 and having a contacting wire 70 connected thereto.

The opposite end of the wire 70 (Fig. 2) 10 is connected to a terminal 71 on the double control switch C. The solenoid 65 is also connected by wires 72 and 73 (Fig. 2) to terminals 74 and 75 on the switch C.

15 *Operation of the selector device*

The operation of the selector device is as follows:—

Whenever a circuit is completed through the wires 72 and 73 and the solenoid 65, the 20 pawl 54 is operated to advance the ratchet 53 and contact 50 from one terminal 42 to the next. Each terminal 42 is connected through its wire 41 to a contact 40 which engages one of five selected terminals 44, by which the 25 blowing of the different ejector pots is controlled.

In Fig. 2, the different terminals 42A, 42B, etc., are shown connected by the wires 41 to corresponding contact members 40 on 20 the spider arms 38A, 38B, etc.

Assuming that the spider 37 is positioned as shown in Fig. 2 and that the contact 50 engages the terminal 42—C, the circuit will 25 pass through a wire 41 to a contact 40, on the arm 38—C, said contact 40 being shown as engaging a terminal 44 connected to the No. 3 ejector.

On the next actuation of the solenoid plunger, the contact 50 will be advanced to 40 the terminal 42—D, which is connected to control the No. 1 ejector.

The contact 42—E controls the No. 2 ejector and the contact 42—F controls the No. 3 ejector.

45 With the spider set in this position, the pots will accordingly be blown in the order 1—2—3. If the spider 37 is turned one space clockwise, the order will be changed to 1—3—2. Another space clockwise, gives the order 1—2, 1—2. The next space produces the order 1—3, 1—3 and the last space operates the ejectors in the order 2—3, 2—3, thus covering all possible combinations of the 55 three ejectors in groups of either two or three.

General operation of the control mechanism

Having described the construction and operation of the mechanism for blowing the 50 ejector pots and of the selector devices for determining the order of operation, I will now describe the general operation of the device.

55 I will first describe the operation when the

control switch C is set for blowing the pots in predetermined sequence.

Line wires L' and L² are connected into the circuit through a double contact single throw switch 77 and suitable fuses, this group of 70 mechanism being indicated by the letter D.

Line wire L² is connected to three of the 75 six terminals of each safety cut-out switch G, one of these switches being provided for each ejector.

The float control switch for the No. 3 ejector is indicated diagrammatically at 80 in the lower right hand corner of Fig. 2. This float switch controls two contacts 81 and 82. When a pot is filled, the float switch operates 80 to close the contacts 81 and 82.

The line wire L' is then connected through the safety switch G, contact 81, a second terminal 83 of the switch G and a wire 84 to the No. 3 green light 85, through which it is connected to a branch of the line wire L' thus completing the circuit.

The first effect of closing the float switch 80 is therefore to light the No. 3 green signal to indicate that the No. 3 pot is full. 80

At the same time the contact 82 closes an interlocking circuit through the terminal 87 of the safety switch, the wire 88, the normally closed contact 89 of the No. 1 magnetic switch F, a wire 90, a normally closed contact 91 85 of the No. 2 switch, and a wire 92 connecting to a terminal 93. From 93, the connection continues through a wire 94 to the magnet coil 95 of the No. 3 magnetic switch F and thence through a wire 96 to a member 97 of 100 the six pole double throw control switch C.

Assuming that this switch is thrown to the left for sequence operation, the circuit continues through the terminal 48 and the wire 45 to the selector arm 38—C, which in turn 105 is connected through a wire 41, contact 50 and wire 70 to the terminal 71 of the switch C and thence to a terminal 98 connected to a branch of the power line L'.

The circuit through the magnet 95 is thus 110 completed by the closing of the contact 82, assuming that neither the No. 1 nor the No. 2 ejectors are being blown.

The magnet 95 then pulls the switch bar 100 of the No. 3 magnetic switch F to the 115 right, closing contacts 101 and 102 and opening contacts 103 and 104. The contacts 103 and 104 are in the interlocking circuits of the No. 1 and No. 2 ejectors, similar to the contacts 89 and 91 previously described, and the opening of these contacts 103 and 104 effectively prevents automatic operation of either of the other ejectors so long as these contacts remain open.

The contact 101 in the No. 3 magnetic 120 switch F controls a so-called "hold in" circuit. When this contact is closed, a return circuit from the magnet 95 is completed through a wire 105, the contact 101 and a wire 106 to the power line L', thus providing 125

a circuit parallel to the circuit through the selector device previously described.

This circuit acts to hold the pneumatic ejector control apparatus in position for blowing the ejector until the operation is completed, regardless of the fact that the contact 50 may have been advanced to its next selective position. The contacts 101 and 102 are frequently designated as the "hold in" switches.

Closing of the contact 102 completes the operative circuit for the pneumatic control devices as follows:

Current from a branch of the power line L' passes through the contact 102 in the magnetic switch F, then through a wire 110 to a terminal 111. A branch wire 112 connects the terminal 111 through the No. 3 red light 113 to the power line L², thus lighting the red signal to indicate that the No. 3 ejector is being blown. The terminal 111 is also connected by a second branch wire 115 and through a terminal 116 in the No. 3 safety switch G to a wire 117 having parallel circuits through the magnet coils controlling the operation of the valves 26 and 27 previously described.

The return circuit from the coils 118 is through a wire 119 and terminal 120 to a branch of the power line L².

When the magnet coils 118 are energized, the valve 26 is opened and the valve 27 is closed to actuate the diaphragm 22 and admit air pressure to the No. 3 pot, as previously described.

It will be seen therefore that the closing of the No. 3 float switch 80 acts first to light the No. 3 green light 85, indicating that the No. 3 pot is full. Simultaneously the contact 82 is closed, completing the operative circuit if the interlocking contacts 89 and 91 in the No. 1 and No. 2 magnetic switches are both closed, indicating that neither one of these ejectors is being blown.

If these switches are closed, the No. 3 red signal 113 is lighted and the magnetic coils 118 are energized to shift the pneumatic connections and admit air under pressure to blow the No. 3 ejector pot. The "hold-in" switches 101 and 102 are also closed, maintaining the circuits during the advance movement of the selector.

Operating connections for the selector

I will now describe the mechanism for advancing the selector contact 50, step by step. For this purpose the terminal 93 previously described is connected through a delayed-action switch 120 (Fig. 2) to a wire 121 and through a terminal 122 of the control switch C to the terminal 74 previously described. From the terminal 74 the circuit is completed through the wire 72, wire 73, contact 75 and switch terminal 124 to the power line L'.

The delayed-action switch is a usual commercial device and in itself forms no part of

my invention. The switch may have a dash pot control or may be otherwise so controlled as to close a few seconds after the closing of the "hold-in" switches 101 and 102.

The pawl mechanism is thus operated to move the selector to the next spider arm 38, thus placing it in position for operating the next ejector in sequence as soon as the No. 3 magnetic switch F returns to normal position, restoring the interlocking circuits.

When the No. 3 pot is emptied, the float switch 80 will move to the left in Fig. 2 to open the contacts 81 and 82, thus extinguishing the green signal, showing that the No. 3 pot is no longer full, and also breaking the circuit through the red signal and through the magnet coils 118, thus interrupting the blowing operation and also extinguishing the red signal to show that the No. 3 pot has ceased blowing.

Random operation

If it is desired to blow the pots in the order of filling, rather than in predetermined sequence, the control switch C will be thrown to the right in Fig. 2, thus cutting out the selector device circuits and the solenoid circuit, and connecting the three magnetic switches direct to the power line L'.

Referring to the No. 3 ejector, the circuit from the magnet 95 will be completed through the wire 96 to the switch terminal 97, from which point a direct connection will be made to the power line L', similar connections being provided from the No. 1 and No. 2 magnetic switches.

With these connections, the closing of the float switch in any ejector will cause the immediate blowing of that ejector, provided the other two ejectors are inoperative, the operation being at random or in hit-or-miss order, as the pots are filled.

Test switches

I have provided test switches E by which any ejector may be blown at any time. If the No. 3 test switch is closed, for instance, a circuit is immediately completed through the wire 115, terminal 116, wire 117, magnet coils 118, wire 119 and terminal 120 to the power line L², while at the same time the branch connection through the terminal 111 and wire 112 illuminates the red light 113.

Similar connections through the No. 1 and No. 2 circuits are controlled by the No. 1 and No. 2 test switches, it being understood that all of the mechanism shown as connected with the No. 3 safety cut-out switch G is duplicated on the No. 1 and No. 2 ejectors.

Conclusion

The circuits for the No. 1 and No. 2 controls are indicated in dotted lines on Fig. 2 and as they are substantial duplicates of the

No. 3 circuits, it is not believed necessary to further describe the operation thereof.

Having described the details of construction and the general operation of my improved control mechanism, it will be seen that I have provided an extremely flexible mechanism.

By throwing the control switch C to the left or right, the operation may be in predetermined sequence or in random or hit-or-miss order. By moving the selector wheel 36 the order may be varied as desired. Three ejectors may be used in 1-2-3 or 1-3-2 order or any two ejectors may be used in 15 1-2, 1-3, or 2-3 order.

Furthermore, any ejector may be rendered inoperative by opening its safety cut-out switch without breaking the interlocking circuits or interfering with the operation of the 20 other two ejectors.

Finally, I have provided the test switches E by which any ejector may be blown at any time, even if only partially full and regardless of the other ejectors which may be at 25 that time in operation.

I have shown the connections for three ejectors, but my invention is applicable to either more or less ejectors, as desired.

Having thus described my invention and the advantages thereof, I do not wish to be limited to the details herein disclosed, otherwise than as set forth in the claims, but what I claim is:—

1. In a sewage ejecting system, a plurality of ejectors, means to vent and fill each of said ejectors, means to blow said ejectors, and automatically controlled means for effecting blowing of said ejectors in predetermined sequence.

2. In a sewage ejecting system, a plurality of ejectors, means to vent and fill each of said ejectors, means to blow said ejectors, automatically controlled means for effecting blowing of said ejectors in predetermined sequence, means for changing said sequence, and additional manually controlled means for blowing any selected ejector, and means to simultaneously prevent the blowing of any other ejector.

3. In a sewage ejecting system, a plurality of ejectors, means to vent and fill each of said ejectors, means to blow said ejectors, automatically controlled means for effecting blowing of said ejectors in predetermined sequence, additional manually controlled means for blowing any selected ejector, and means to simultaneously prevent the blowing of any other ejector.

4. In a sewage ejecting system, a plurality of ejectors, means to blow said ejectors in predetermined sequence, and means to simultaneously and automatically prevent the blowing of any other ejector while any one ejector is being blown.

5. In a sewage ejecting system, a plurality

of ejectors, automatic control means for blowing said ejectors in predetermined sequence, automatic control means for blowing said ejectors in the order of filling, and means to place said ejectors under control of the desired automatic means. 70

6. In a sewage ejecting system, a plurality of ejectors, automatic control means for blowing said ejectors in predetermined sequence, automatic control means for blowing said ejectors in the order of filling, and a manual device to place said ejectors under control of the desired automatic means. 75

7. In a sewage ejecting system, a plurality of ejectors, automatic control means for blowing said ejectors in predetermined sequence, automatic control means for blowing said ejectors in the order of filling, a manual device to place said ejectors under control of the desired automatic means, additional manually controlled means for blowing any ejector at any time, and means to simultaneously prevent the blowing of any other ejector. 80

8. In a sewage ejecting system, a plurality of ejectors, means to vent and fill each of said ejectors, means to blow said ejectors, separate control connections for indicating and blowing each ejector, and means to shift said connections to a predetermined succeeding 95 ejector upon the blowing of a particular ejector.

9. In a sewage ejecting system, a plurality of ejectors, separate control connections for indicating and blowing each ejector, and means to shift said connections to a predetermined succeeding 100 ejector upon the blowing of a particular ejector and before said blowing is completed.

10. In a sewage ejecting system, a plurality of ejectors, means to vent and fill each of said ejectors, means to blow said ejectors, a control mechanism determining the order of blowing thereof, said mechanism including a selector having a rotary step by step movement, and means to vary the selective effect of said step by step movement. 105

11. In a sewage ejecting system, a plurality of ejectors, means to vent and fill each of said ejectors, means to blow said ejectors, a control mechanism determining the order of blowing thereof, said mechanism including a selector having a rotary step by step movement, said selector having a plurality of circuit closing contact arms and said control mechanism 115 including a plurality of terminals separately controlling each ejector, said terminals being arranged in the path of said contact arms.

12. In a sewage ejecting system, a plurality of ejectors, means to vent and fill each of said ejectors, automatically controlled means to blow said ejectors, and interlocking control mechanism effective to prevent the automatic operation of more than a single ejector at any given time, said mechanism including sepa- 125

- rate control connections for blowing each ejector and means to shift said connections to a succeeding ejector upon the blowing of a preceding ejector.
- 5 13. In a sewage ejecting system, a plurality of ejectors, means to blow said ejectors, magnetic switches controlling said blowing means, and interlocking control circuits for said switches, whereby the operation of any one magnetic switch simultaneously disables all of the other magnetic switches.
- 10 14. In a sewage ejecting system, a plurality of ejectors, means to vent and fill each of said ejectors, means to blow said ejectors, a separate switch controlled by a float for each ejector, a signal circuit directly operated by said switch, and a blowing circuit jointly controlled by circuit connections through the several switches.
- 15 15. In a sewage system, a plurality of ejectors, switches effective on closing to blow said ejectors, a selective device determining which switch shall be closed, and a delayed action device effective thereupon to select a different switch.
- 20 16. In a sewage ejecting system, a plurality of ejectors, means to vent and fill each of said ejectors, means to blow said ejectors, a control mechanism determining the order of blowing thereof, said mechanism including a selector having a rotary step by step movement, automatically actuated means to operate said selector through its step by step movement, and means to vary the selective effect of said step by step movement.
- 25 17. In a sewage ejecting mechanism, a plurality of ejectors, means to vent and fill each of said ejectors, means to blow said ejectors, a control mechanism determining the order of blowing thereof, said mechanism including a selector having a rotary step by step movement, said selector having a plurality of circuit closing contact arms, and said control mechanism including a plurality of terminals separately controlling each ejector, said terminals arranged in the path of said contact arms and automatically actuated means to operate said selector through its step by step movement.
- 30 18. In testimony whereof I have hereunto affixed my signature.
- 35 HAROLD E. ADAMS.
